(57) **CLAIM**

The ornamental design for a printer for printing 3-dimensional objects, as shown and described.

DESCRIPTION

FIG. 1 is a perspective view of a printer for printing 3-dimensional objects, the printer including a movable door, the movable door illustrated in a closed position;

FIG. 2 is a top view of the printer illustrated in FIG. 1;

FIG. 3 is a front elevation view of the printer illustrated in FIG. 1;

FIG. 4 is a side elevation view of the printer illustrated in FIG. 1, with this view being representative of each of a left side, a bottom side, a rear side and a right side of the printer; and,

FIG. 5 is a perspective view of the printer illustrated in FIG. 1, with the movable door illustrated in an open position.

1 Claim, 3 Drawing Sheets
